APPARATUS FOR CLOSURE ASSEMBLY

Daniel S. Holt, Lancaster, Pa., assignor to Armstrong Cork Company, Lancaster, Pa., a corporation of Pennsylvania

Application May 18, 1933, Serial No. 671,636

18 Claims. (Cl. 49—1)

This invention relates to a mechanism for inserting rods and similar fusible members in bottle closures and more particularly for inserting glass applicator rods into molded bottle closures such as "Bakelite" caps or the like in which the glass rod is heated adjacent the end to be inserted in the closure and upon fusion placed in an opening provided in the closure and pressed therein until the glass rod has cooled sufficiently to harden.

Glass rods have been inserted in bottle closures for sometime and have been held in position by means of adhesive. Such closures are unsightly and the adhesive is not particularly suited for certain materials which are bottled and which come into contact with the rod and closure. The glass rods have been inserted heretofore by hand due to the nature of the adhesive employed and the assembling operation has been expensive and slow.

According to my invention a machine is provided which is substantially completely automatic in operation, produces a highly satisfactory closure unit and is adapted for production operation. It is an object of my invention to provide a mechanism which will operate upon applicator rods of various sizes and will insert them into caps which may be of different peripheral contour and size. It is a further object of my invention to provide a machine which is readily adjustable so that short runs may be economically carried out on a single machine.

In order that my invention may be more readily understood, I will describe the same in connection with the accompanying drawings in which,

Figure 1 is a top plan view of my machine with certain parts broken away for clarity of illustration;

Figure 2 is a sectional view taken along the line II—II of Figure 1;

Figure 3 is an isometric view illustrating the rod moving cam;

Figure 4 is an isometric view of the unit raising and lowering track;

Figure 5 is a side elevation of one of the rod holding and manipulating units;

Figure 5b is a side elevation showing my rod positioning mechanism;

Figure 6 is a view similar to Figure 5 illustrating a preferred mechanism for removing completed closures from the machine;

Figure 7 is a detail isometric view of the rod holding mechanism; and

Figure 8 is an isometric view of a completed closure with applicator rod in position therein.

My machine comprises a supporting table 2 secured to a sleeve 3 by means of a set screw 4. The sleeve 3 rotates about a stationary shaft 5 and is driven by a suitable gearing mechanism indicated generally at 6. A plurality of the rod holding and moving mechanisms illustrated in Figures 2 and 5 are secured to the table and comprise a supporting plate 7 provided with openings through which passes a rod 8. Adjustably secured to the rod 8 by means of a locking collar 9 is a resilient finger 10 which serves to hold an applicator rod against the bracket 11. Tension is placed on the spring 10 by moving the collar 9 toward the bracket 11. Adjustably secured to the rod 8 is a cam follower 12 adapted to contact with the surface of the cam 13 (illustrated in Figure 3) which is adjustably secured to the stationary shaft 5. The follower 12 is provided with a drilled opening adapted to encircle the rod 8 and is slotted and provided with an adjusting screw 14 which is employed to securely position the follower on the rod 8 after proper adjustment is had. A counterweight 15 is also adjustably secured to the shaft 8 by means of a drilled and slotted opening similar to that employed on the cam follower.

In operating the machine, a glass applicator rod is inserted into the holding bracket 11 and is resiliently held in position by means of the holding finger 10. The end of the rod is heated in order to fuse the same and in my preferred embodiment I provide a gas flame to accomplish this fusing. The gas supplying mechanism comprises a source of gas supply 16 which is carried by a pipe 17 into a tank 18. The tank is provided with an opening through which the sleeve 3 passes. The tank is held stationary by means of brackets 19 secured to the frame of the machine. This tank is substantially completely filled with water W. The supply pipe 17 extends above the surface level of the water and projects into an inverted tank 20 which is secured to the sleeve 3 by means of brackets 21. This tank extends below the surface of the water W in the tank 18 and provides an effective gas seal. The tank 20 rotates with the sleeve whereby a continuous supply of gas is fed to the burners 22 which are attached to the top of the tank 20 and are held in position under the table by means of angles 23. The table is provided with a plurality of openings 24 through which the gas flames pass.

In order to insure that only the tip of the glass rod will be exposed to the flame, I provide an adjusting device which is illustrated in Figures 5 and 5b. This adjusting mechanism comprises essentially a plunger 25 passing through an opening in the table 2 and through a similar opening in the supporting bracket 26. A stop 27 is provided on the plunger 25 which stop engages the flat surface of the bracket 26 and positions the plunger normally flush with the top of the table 2. A cam 28 secured by a bracket 29 to the main frame of the machine lies in the path of travel of the plunger 25 and causes it to rise vertically. The plunger contacts with the end of the applicator rod R which has been inserted in the holding bracket 11 and raises the rod and spaces it a predetermined distance from the surface of the table 2. The distance is fixed so that only the tip of the rod R will come into contact with the gas flame supplied by the burner 22 through the opening 24 in the table. It will be noted from examination of the right hand portion of Figure 2 that the glass rods are in horizontal position when the heat is applied. In order to rotate the rods from the vertical position (illustrated in Figure 5) through 90 degrees to the heating position (illustrated in Figure 2) the cam 13 is provided. This cam is secured to the stationary shaft 5 and the table 2 rotates about the cam; the followers 12 following the surface of the cam. When the followers 12 are in the position illustrated in Figure 5, they travel under the portion 30 of the cam being urged into that position by the counterweight 15. When the followers engage the shoulders 31 of the cam, however, they are caused to rotate through a 90 degree angle, thereby raising the counterweight 15 which urges the flat surface of the follower 12 into contact with the surface 32 of the cam and the rods are held in horizontal position as illustrated in the right hand portion of Figure 2. When the machine is set into operation, the followers 12 are adjusted with respect to the shaft 8 so that the rods R are in horizontal position when the flat surface of the follower is in contact with the surface 32 of the cam.

The bottle closures 33 which are provided with a well 34 adapted to receive the rods R are positioned on the table by means of a positioning plate 35 which is secured to the table 2 by means of a screw 36 passing through a slot 37 provided in the positioning plate. This plate is provided with a cut-out portion adapted to receive the closure and position it with respect to the rod holding bracket 11 in order that the rods R may be inserted into the center of the well 34. The holding plate 35 may be readily adjusted by loosening the screw 36 whereby the plate 35 may be pivoted around the screw or may be adjusted circumferentially by movement in the slot 37.

The heat is applied to the end of the rod R as the table continues to rotate. After the tip of the rod has been brought to the fusion point the rod is returned to the vertical position and forced into the well of the cap. This is effected by means of arms 38 which are adjustably secured to the brackets 39 and are guided in ways 40. Each arm is provided with a weight 41 secured by means of a wire 42 to the arm 38. A roller 43 is secured by means of a screw 44 to the outer end of each arm. The roller 43 rides upon the track 45. This track is adjustably secured to the stationary shaft 5 by means of a pair of lock nuts 45' whereby the track may be raised or lowered depending upon the length of the applicator rods

being inserted. The track 45 and arms 38 are so adjusted that sufficient pressure is applied to the end of the rod R to properly position the rod in the well and to effect union between the rod and the closure.

When the cam follower reaches the edge 46 of the cam 13 the counterweight 15 causes the rod 8 to rotate through a 90 degree angle whereby the rods are held in substantially vertical position. Adjusting screws 47 are provided which contact with the counterweight 15 and are so positioned that when the counterweights are in contact therewith the rods R are held in vertical position. As mentioned above the rods are now fused at their tip and are ready for insertion into the well provided in the closure. The cam 13 and the track 45 are circumferentially adjustable and are set so that immediately the cam follower returns the fused rod to the vertical position the roller 43 descends from the surface 48 of the track 45 toward or onto the surface 49. This causes the arm 38 to contact with the end of the rod R and place the fused end of the rod into the well of the cap (left hand portion of Figure 2). It will be noted by reference to Figure 4 that the track is provided with an abrupt drop from the portion 48 to the portion 49. This is provided so that the fused rods will be thrust quickly into the molded closures and will not have an opportunity to cool until they are in place. Also, if the well in the closure and the rod were not in perfect alignment and the rod were inserted slowly into place, the wall of the well might be burned through. When rapid insertion is had, however, the rod tends to properly position itself in the well and will move slightly inaccurately positioned closures into proper alignment. The fused end of the rod being relatively soft is caused to flow or upset by the continued pressure, filling the well of the closure and in some instances slightly scorching or burning the inner surface whereby an irregular surface is formed on the interior of the well and a highly effective bond is obtained between the well and the rod. In most cases, the rods will support the arms so that the rollers 43 are not in actual contact with the track 45, whereby the entire weight is taken by the rod and the rod is firmly positioned in the closure until it hardens.

It is advisable that only the tip of the rod be heated as otherwise the portion of the rod above the well will be bent or otherwise deformed upon application of pressure by the arm 38 forcing the rod into the well. The pressure is continued until the rods have had an opportunity to set or harden, which setting or hardening may be substantially instantaneous upon upsetting. The rollers are then raised on the track 45 and the completed closure with the rod inserted therein is removed from the machine. The removal of the completed closure is effected by means of a pair of resilient fingers 50 (Figures 1 and 6) which engage the completed closure as it travels on the table 2. The fingers are so positioned that they engage a portion of the rod as well as the cap proper and move them away from the holding bracket into a chute 51. The removing fingers are adjustably secured to a bracket 52 by means of a screw 53 passing through a slot 54 provided in the fingers. The bracket 52 is secured to the frame of the machine.

In my preferred embodiment, illustrated in Figure 1, I have provided a pressure disk 55 rotatably secured to a plate 56. This disk is provided to force the closures into contact with the

positioning plate 35 which is preferably contoured to fit the closure in order to assure accurate positioning. A spring 57 is provided which yieldingly urges the roller into contact with the 5 surface of the cap and an adjusting plate 58 threaded into a bracket 59 is employed to limit the movement of the disk 55 toward the caps.

Suitable mechanism may be provided for feeding the closures and rods to the machine. It has 10 been found, however, that a single operator may conveniently insert the rods and closures while my machine is operating at a relatively high speed. The rods are first inserted and after positioning thereof has been effected, the closures 15 are fed to the machine.

I have described and illustrated my invention using a moulded closure and a glass applicator rod as typical examples of materials to be operated upon. It will be understood, however, that other 20 types, such as metal or ceramic closures may be used and members which soften upon the application of heat may be employed, such as glass and certain synthetic resin composition rods, and the like.

25 While I have described certain preferred embodiments of my invention, it will be understood that the invention may be otherwise embodied and practiced within the scope of the following claims.

30 I claim:

1. In a machine for applying a fusible applicator to a closure, holding means for the fusible applicator, heating means effective for softening the fusible applicator, means positioning a closure 35 with respect to said holding means, and means effecting relative movement between said applicator and said closure to effect union therebetween subsequent to the application of heat to said applicator.

40 2. In a machine for applying fusible applicators to closures, closure positioning means, applicator holding means, heating means effective for softening an applicator, said holding means being rotatable to expose the end of said applicator to 45 heat from said heating means and rotatable to position said applicator in cooperative relationship with said closure positioning means and means effective for moving said applicator in the applicator holding means into the closure.

50 3. In a machine for applying fusible applicators to closures, rotatable closure holding means, applicator holding means rotatable with said closure holding means and moveable with respect thereto, heating means effective for applying heat 55 to an applicator in said applicator holding means during a portion of a revolution thereof to effect softening of the applicator, and stationary means effective for rotating said applicator holding means with respect to said closure holding means.

60 4. In a machine for applying fusible applicators to closures, holding means for the applicator, heating means effective for softening the fusible applicator, means positioning a closure with respect to said holding means, pressure means urging said applicator into said closure and means for controlling said pressure means.

65 5. In a machine for applying fusible applicators to closures, holding means for the applicator, heating means for softening the fusible applicator, means positioning a closure with respect to said holding means, pressure means for urging said applicator into said closure, means for rotating said holding means, and means for controlling said pressure means, said rotating means and said

controlling means being circumferentially adjustable.

6. In a machine for applying fusible applicators to closures, holding means for the applicator, heating means effective for softening the fusible 5 applicator, means positioning a closure with respect to said holding means, pressure means urging said applicator into said closure and means for controlling said pressure means, said controlling means being adjustable vertically where- 10 by applicators of various lengths may be operated upon.

7. In a machine for applying fusible applicators to closures, rotatable closure holding means, applicator holding means movable with said closure 15 holding means and rotatable with respect to said closure holding means, heating means effective for applying heat to an applicator in said holding means during a portion of a revolution of said closure holding means to effect softening of the 20 applicator, pressure means urging said applicator into said closure and stationary means effective for rotating said applicator holding means with respect to said closure holding means and controlling said pressure means.

25 8. In a machine for applying a fusible applicator to a closure, holding means for the fusible applicator, means for positioning said applicator in said holding means, heating means effective for softening the tip of said fusible applicator and 30 means for urging said applicator into a closure spaced in cooperative relationship therewith.

9. In a machine for applying a fusible applicator to a closure, closure positioning means, means for holding said applicator, means for positioning said applicator in said holding means, means associated with said holding means effective for moving said applicator into the path of a heating flame and effective for moving said applicator away from said flame and into cooperative relationship with said closure and means effecting relative movement between said applicator and said closure to effect union therebetween subsequent to the application of heat to said applicator.

40 10. In a machine for inserting a fusible applicator into a closure, closure positioning means, reciprocable pressure applying means superposed to said positioning means, applicator holding means interposed between said pressure means and said positioning means and means for imparting reciprocating motion to said pressure means.

45 11. A machine for applying a fusible applicator to a closure comprising a rotatable support, closure positioning means, applicator holding means 55 and pressure applying means secured to said support, said applicator holding means being interposed between said positioning and said pressure means, stationary control means for said pressure means about which said support rotates, said control means being effective for causing relative movement between said pressure means and said support.

60 12. In a machine for applying a fusible applicator to a closure, means for slidably holding an 65 applicator, reciprocable pressure applying means superposed to said holding means, closure supporting means below said holding means, means for positioning said closure on said support and means for imparting reciprocating motion to said pressure means whereby an applicator held in said holding means is urged into contact with a closure on said support and said holding means firmly positions said applicator during the application of pressure.

13. A machine for applying a fusible applicator to a closure comprising heating means, means for slidably holding an applicator, reciprocating pressure applying means, closure supporting means in cooperative relationship with said applicator holding means, control means for said holding means effective for moving said holding means toward and away from said heating means and control means for said pressure means effective for causing relative movement between said pressure means and said supporting means after said holding means has moved away from said heating means to urge said applicator into engagement with said closure.
14. A machine for applying a fusible member to a closure comprising holding means for said fusible member, means positioning a closure to receive said member with respect to said holding means, heating means effective for softening the fusible member, means for causing relative movement between said heating means and said holding means to position the fusible member in the zone of the heating means and means for effecting relative movement between the fusible member in said holding means and said closure.
15. A machine for applying fusible members to closures comprising a rotatable support, a plurality of holders for fusible members on the support, closure positioning means on the support in cooperative relationship with the holders, pressure applying means for urging a fusible member into engagement with a closure on the support, heating means effective for softening the fusible member, a stationary control for the holders adapted to move the fusible members into and out of the zone of the heating means upon rotation of the support, and a control for the pressure applying means, one of said controls being adjustable with respect to the other whereby the application of pressure may be controlled with respect to the removal of the members from the heating zone.
16. A machine for applying fusible members to closures comprising a holder for a fusible member, heating means for softening a portion of the fusible member, a support for a closure, and means for effecting relative movement between the fusible member and the closure to effect union therebetween subsequent to the application of heat to said fusible member.
17. A machine for applying fusible members to closures comprising a holder for a fusible member, heating means for softening a portion of the fusible member, means for moving the holder toward and away from the zone of the heating means to place the fusible member in the heating zone and remove it therefrom, a support for a closure and means for urging the fusible member into the closure to upset the fused portion thereof.
18. In a machine for applying a fusible applicator to a closure, means for holding said applicator, means for positioning said applicator in said holding means, means for exposing the tip of said applicator to a heating flame, with the axis of said applicator being at substantially right angles to the direction of said flame to soften the same, means for supporting a closure and means for urging the softened tip of said applicator into a closure on the support.

DANIEL S. HOLT. 35
